[57] CLAIM

The ornamental design for a stove as shown, and described.

DESCRIPTION

FIG. 1 is a top, front and right side perspective view of a stove showing my new design;

FIG. 2 is a top plan view thereof; and

FIG. 3 is a right side elevational view thereof, the undisclosed left side being a mirror image of that shown, the rear being plain and unornamented, and the stack element being shown broken-away to indicate indeterminate length.

FIG. 1

FIG. 2

FIG. 3
